UNITED STATES PATENT OFFICE.

MARION W. PITNER, OF CHICAGO, ILLINOIS.

FIXTURE-SUPPORT.

No. 911,441.

Specification of Letters Patent.

Patented Feb. 2, 1909.

Application filed May 29, 1907. Serial No. 376,314.

To all whom it may concern:

Be it known that I, MARION W. PITNER, a citizen of the United States, residing at Chicago, in the county of Cook and State of Illinois, have invented new and useful Improvements in Fixture-Supports, of which the following is a specification.

This invention relates generally to improvements in fixture supports, and particularly to wall or ceiling plates or brackets for lighting fixtures, such as for the lamps and controlling connections of gasolene lighting systems, the main object of the invention being to provide a supporting plate or bracket which may be employed either for the purpose of supporting a lamp and connecting the hydrocarbon feed pipe therewith or supporting and connecting a controlling valve with the hydrocarbon feed or supply pipe, whereby the supply of the hydrocarbon to all the lamps on a floor may be controlled from a given point.

The invention consists of a device of the character described embodying certain improved features of construction, combination and arrangement of parts, as will be herein-after fully described and claimed, reference being had to the accompanying drawing, forming a part of this specification, in which:

Figure 1 is a view in side elevation, the canopy appearing in section, of a wall plate or bracket constructed in accordance with my invention shown in use as a lamp support and hydrocarbon feed pipe connection. Fig. 2 is a similar view showing the bracket employed as a support for a cut-off valve controlling the feed of hydrocarbon from the supply pipe to a lamp or a series of lamps. Fig. 3 is a section through the controlling valve shown in Fig. 2. Fig. 4 is a central vertical section through the wall plate or bracket. Fig. 5 is a front elevation of the same.

Referring to the drawing, the numeral 1 designates the improved wall or ceiling plate or bracket, which comprises a body or attaching plate 2, of any preferred form, and which is provided with a desired arrangement of openings 3 for the passage of screws or other fastening devices to secure the same to a wall, ceiling or other suitable support. Integral with the body or attaching plate and projecting forwardly therefrom is a socket member 4 internally screw-threaded at its

outer or forward end, as at 5, and having the rear portion of its bore or passage smooth-surfaced to form a combined hydrocarbon feed channel and catch basin or chamber 6. A nipple 7 is integral with the upper rear portion of the socket 4 and extends vertically therefrom and is provided with external screw-threads 8 and a bore or passage 9 communicating at its lower end with the said channel and chamber 6.

In Fig. 1 I have shown the wall or bracket plate employed as a support for a lamp fixture 10 and connection for the hydrocarbon supply or feed tube or pipe 11 leading from the hydrocarbon reservoir. As illustrated, the lamp fixture 10 is provided with a feed pipe 12 located above its generator pipe 13 and threaded at its rear end as at 14, for insertion into the screw threaded end 5 of the socket 4, by which the lamp is supported from the bracket. The hydrocarbon feed pipe 11 is connected with the nipple 7 in any suitable manner, as by providing it at its connecting end with a tapered jam or metallic packing plug 15 engaging the upper end of the nipple and partially projecting into the passage 9 and retained in position by an internally threaded packing cap or nut 16 engaging the screw threads 8, whereby the supply pipe is attached to the bracket plate in such a manner as to prevent any possibility of leakage of the hydrocarbon at the connecting joint. A canopy 17, of the form and construction ordinarily employed, in connection with electric and gas lamp fixtures, may be secured upon the rear end of the pipe 12 to shield and inclose the bracket and impart an ornamental finish at the supporting point. This canopy is provided as usual with an opening for the passage of the pipe 12 by which it is slidably fitted thereon so as to permit ready access to the bracket when occasion requires, and may be secured in position by set screw or other desired fastening 18.

In Fig. 2, wherein the bracket is illustrated as a feed pipe connection and support for a cut-off valve controlling the supply of hydrocarbon to a lamp or series of lamps, the hydrocarbon supply pipe is connected with the nipple 7 in the manner previously described. The controlling valve here shown consists of a casing 19 externally threaded at its inlet end for insertion into the socket 5 and provided with a feed passage 20 and a suitable

type of screen 21 for filtering the hydrocarbon in its passage so that the impurities will be retained in the basin or chamber 6. The specific construction of this valve is immaterial to the present application, as it is not claimed herein but forms the subject-matter of a separate application, but, for the purpose of indicating its mode of use in connection with the bracket, it may be stated that 10 as illustrated the valve casing is provided with a cut-off valve 22 controlling the passage 20, which latter is in communication with an externally threaded discharge nipple 23 to which a feed pipe 24 leading to an elevated burner or all of a series of burners on a floor is coupled similar to the manner in which the supply pipe 11 is coupled to the bracket nipple 7. The bracket accordingly 15 may be employed as a support for a valve, such as described, located at any convenient point so as to be readily accessible for the purpose of controlling the feed of the hydrocarbon from the supply pipe to a lamp located at any desired elevation or to a series 20 of lamps or to all the lamps on the floor of a building. The valve as thus arranged will serve as a main valve of the type required by various fire insurance companies to enable the hydrocarbon to be completely cut off 25 from the source of supply to the burners in a

room or all the burners on a floor, as will be readily understood.

The bracket may also be used as a connecting medium or combined support and pipe connection in various relations and for various purposes in hydrocarbon and other lighting systems, and therefore its use in general is not restricted to either of the present disclosures.

Having thus fully described the invention, 40 what is claimed as new is:—

A fixture support for hydrocarbon lighting systems comprising a perforated body plate, a boss projecting forwardly from the upper central portion of said plate and formed with a bore of uniform diameter internally screw-threaded at its outer end and smooth-surfaced at its inner end, and a nipple extending upwardly at right angles from the boss in advance of the plate, said nipple being externally screw-threaded and provided with a bore of less diameter than the bore of the boss and intersecting the said smooth-surfaced inner end thereof.

In testimony whereof, I affix my signature 55 in presence of two witnesses.

MARION W. PITNER.
